UNITED STATES PATENT OFFICE

ALCUIN E. KINTNER, OF PAINESVILLE, OHIO

RAILROAD TRACK AND RAILROAD TRUCK

Application filed February 18, 1929. Serial No. 340,672.

The present invention, relating, as indicated, to railroad tracks and railroad trucks, has more particular reference to transportation systems of the type which employ positively acting means for retaining the trucks on the rails and for increasing the pressure with which the wheels of the former bear against the tread surfaces of the latter, and its primary object is to provide, in an organization of this character, improved means for preventing the truck wheels from leaving the rails, improved means for increasing the force with which such wheels bear on the rails, improved means for braking the motion of the truck, and improved means for moving the track engaging apparatus of the truck to and from its operative position with relation to the rails.

More specifically, my invention contemplates providing a track made up of parallel rails having projecting flanges and a truck having wheels for coasting with the tread surfaces of such rails and devices for cooperating with such flanges, as well as means operable to either elevate such devices for increasing the force with which such wheels bear against the rails or to both elevate such devices for increasing such force and to apply brakes to such wheels. In other words, such devices can be used simply for increasing the tractive effort which the wheels are able to exert before slipping on the rails, or to assist the wheel brakes in slowing down or stopping the truck. In the vicinities of switches and crossings, my invention contemplates employing plain or unflanged running rails in combination with stationary ramps for raising the rail flange engaging devices to their inoperative positions and for holding them above the level of the intersecting rails or switch parts until the crossing or switch has been passed and the track engaging devices can again be safely lowered to their normal positions. These devices are preferably revoluble about vertical axes and as above intimated their mounting consists of a vertically reciprocable support arranged for movement by the truck and track means provided for this purpose.

My invention presents the following,

among other advantages; higher rates of speed are practicable because the cooperating truck rollers and rail flanges are effective to prevent the truck wheels from leaving the rails; the truck can be more rapidly accelerated and decelerated and is capable of pulling heavier loads and stopping them within a shorter distance because of the improved means for preventing slippage of the wheels; the weight of the trucks and their supported bodies or cars can be greatly reduced because dead weight as a means of obtaining adequate tractive effort and braking effectiveness is eliminated; safer and stronger trucks are provided; less costly, lower and lighter rails can be employed; and a more simple, positive and reliable means is provided for moving the track engaging devices to their inoperative positions when switches and crossings must be passed and such devices raised above the tops of the intersecting rails.

To the accomplishment of the foregoing and related ends, said invention, then, consists of the means hereinafter fully described and particularly pointed out in the claims; 75 the annexed drawings and the following description setting forth in detail certain means of carrying out the invention, such disclosed means illustrating, however, but one of various ways in which the principle of the invention may be used.

In said annexed drawings:—

Fig. 1 is a side elevational view which shows an illustrative embodiment of my invention; Figs. 2 and 3 are vertical longitudinal sections through the track and truck organization shown in Fig. 1; Figs. 4 and 5 are transverse sections which show the subtruck in its lowered and raised positions; Fig. 6 is a plan view; Fig. 7 is a longitudinal section which corresponds to the transverse section shown in Fig. 5; Fig. 8 is a transverse sectional view of a modified rail; Fig. 9 is a fragmentary and partly sectional view which shows a modification of the rail flanges and subtruck rollers; Fig. 10 is a plan view of a modified track arrangement; Figs. 11 and 12 are transverse sectional views through a modified subtruck and track arrangement; and 100

Fig. 13 is a bottom plan view of the subtruck shown in Figs. 11 and 12.

That embodiment of my invention which is here shown for purposes of illustrating the principles involved consists broadly in two parts, the first being a track 10 and the second being a truck 11. As ordinarily constructed, the track 10 is made up of the two spaced and parallel rails 12, but in the vicinity of switches and intersections such track 10 additionally comprises the intermediate ramps 13. The rails 12 are secured to the transverse ties or sleepers 14, and each is formed with a base 15, a web 16, and a head 17 which is provided with an outwardly directed flange 18. The ramps 13 are formed in the manner illustrated in Fig. 7; in other words, each has the end portions 19, the inclines 20, and an intermediate and horizontal portion 21 which presents a tread surface 22. It will be understood that the ramps 13 and the cross rails (not shown) are suitably arranged at their points of intersection, and that such arrangement provides for permitting of the unobstructed passage of the truck wheels which coact with the running rails. For a purpose which will later appear, the running rails, for some distance in each direction from a crossing or switch, are formed with plain heads; otherwise stated, the flanges 18 are omitted.

The second part of my invention, the truck 11, comprises the side frames 23, the revolvably mounted axles 24, and the wheels 25. Such side frames are secured together by the transverse rods 26, and each is provided with the inwardly directed parts 27. These parts are perforated as at 28, and through such perforations pass the bars 29. At their outer ends, the bars 29 are pivotally connected to the brake shoes 30, and at their inner ends, such bars are pivotally attached to the members 31. As will be apparent from an inspection of Fig. 3, the members 31 and the bars 29 constitute toggles whereby the brake shoes are moved relatively to the tread surfaces of the wheels 25. The operating mechanism for such toggles includes a shaft 32 which is revolvably journaled in the side frames 23 and which extends through the elongated holes 33 in the members 31. This shaft carries the cams 34, and these cams are disposed beneath the blocks 35, such blocks being secured to the members 31. The blocks 35 are so arranged that the members 31 will be forced upwardly and the brakes applied only when the shaft 32 is revolved in a clockwise direction (Fig. 3). Inwardly of the members 31 are the hangers 36. These hangers are formed with the projecting stops 37 which coact with the lower two of the rods 26, and their upper portions are provided with elongated holes 38, through which passes the shaft 32, as well as with the flanges 39 which are disposed above the cams 40. Such

cams are secured to the shaft 32, and when they are revolved in either direction the hangers 36 will be elevated. At their lower ends the hangers 36 support a subtruck 41, and this part, on its under side, carries the rollers 42 which are revolvably journaled in the brackets 43. The outer ends of the subtruck 41 project beyond the limits of the side frames 23, and such ends are formed with the bosses 44. These bosses are bored as at 45 and 46 to provide the ledges 47. Disposed between such ledges and the heads 48 of the pins 49 are the thrust bearings 50, and between the lower sections of such pins and the walls of the bore 46 are the roller bearings 51. To the lower and projecting ends of the pins 49 are secured the rollers 52, and these rollers are provided with the peripheral grooves 53.

Normally, the grooves 53 of the rollers 52 straddle the flanges 18 of the running rails 12, and the flanges 54 of the wheels 25 coact with the inner faces of the heads 17. If the truck 11 is a tractor, and if it is desired to increase the draught force beyond that at which the wheels begin to slip on the rails, the lever 55 (Figs. 2 and 3) is swung to the right. This will be effective to oscillate the cams 40 in a counterclockwise direction, and such cams, during this movement, will raise the flanges 39 and the subtruck 41. The rollers 52 will therefore move upwardly with relation to the running rails, and the lower horizontal surfaces of their grooves 53 will engage with the under surfaces of the flanges 18. The running rails will therefore be clamped more or less firmly between the truck wheels and the subtruck rollers, and as a consequence the tractor wheels will be able to exert a greater draught. The lever 55 may be operated in any suitable manner. The operating mechanism herein shown consists of an electric motor 56 which carries a pinion (not shown) on the end of its armature shaft. This pinion meshes with the segmental gear 57, and this gear is attached to the lever 58. The lever 58 is pivoted as at 59, and its lower end is connected to the rod 60. The remote end of the rod 60 connects with the lever 55. Such motor is reversible and the torque which it exerts is variable in both directions. This makes it possible to regulate the tractive effort which the truck wheels exert; when heavy loads are being drawn or when the running rails are slippery, the rollers 52 can be elevated with greater force than when lighter loads are being drawn or the track is dry.

When the truck 11 or the vehicle of which it forms a part is to be stopped or slowed down, the lever 55 (Figs. 2 and 3) is swung to the left. The cams 34 and 40 will then be oscillated in a clockwise direction, and both the flanges 39 and the blocks 35 will be ele-

vated. Such elevation of the blocks 35 will result in forcing the shoes 30 against the tread surfaces of the wheels 25 in the manner hereinafter explained, and such elevation of the flanges 39 will result in lifting the rollers 52. The action of these means will quickly bring the truck 11 to the desired speed.

When the truck 11 is passing over a switch or crossing, the subtruck 41 is in the raised position shown in Figs. 5 and 7, and the rollers 52 and 42 are above the tops of the intersecting rails. As clearly shown in such figures, this raising from the lower or operative position is effected by the ramps 13 and the rollers 42. As the truck proceeds towards a crossing or intersection, such rollers engage with the inclined portions 20 and the subtruck is elevated. The rollers 42 then pass onto the horizontal portions 21 and ride thereon until the obstructions have been passed. Such rollers then move down the inclined portions at the far ends of the ramps and the subtruck again assumes its operative position. The absence near switches and crossings of the rail flanges with which the track engaging devices cooperate permits of the above explained lifting and lowering of the subtruck to which such devices are attached, but the sections of the track at points removed from the switches and intersections are, as above noted, provided with flanges which act in such a manner as to positively prevent any separative movement of the engaging rollers.

In Fig. 8 there is shown in transverse section a modified rail structure which may be used in place of the one previously described. This consists of a standard rail 61 to which is secured, as by the bolts 62, a plate 63. Such plate has a flange 64 which serves the same purpose as the integral flange illustrated in the preceding figures. The lower part 65 anchors the aligned rails together, and in installing an assembly of this type, the joints between the plates are preferably arranged alternately in order to give additional strength and to avoid coincidence of the joints traversed by the wheels and rollers of the truck.

Fig. 9 illustrates a modified form of my invention, and this modification consists in upwardly inclining the rail head flanges 66 and in correspondingly tilting the subtruck rollers 67. When this arrangement is employed a slight change in the bosses 68 is necessary in order to compensate for the altered positions of the roller shafts, and it is found that any degree of angularity is feasible and that the rollers (the bosses 68 being suitably formed) can even be adapted for revolving in vertical planes. As shown, such rollers revolve in planes which are inclined at about fifteen (15) degrees from the horizontal.

In Figs. 10 to 13 inclusive, a still further modification of my invention is illustrated, and in comparison with that embodiment which was explained in connection with Figs. 1 to 7 inclusive, this modification is advantageous in that it does not require an extension of the subtruck controlling ramps across any switch parts or intersecting tracks. With a view to realizing this advantage, the ramp rails 69 are inclined outwardly as well as upwardly, and the subtruck 70 is provided with the pivotally supported rollers 71 and with the ramp engaging wheels 72. Such rollers are revolubly journaled on pins or shafts which project outwardly from the hinged or pivoted members 73, and the wheels 72 are revolubly connected with the collars 74. These collars are slidably mounted upon a shaft 75 which is centrally fixed in the bracket 76, and the links 77 extend from thin bosses 78 to the pivoted members 73. When the wheels 72 engage with the ramp rails 69, the subtruck 70 is elevated in about the same manner as has been previously explained, and the collars 74 are moved outwardly towards the main running rails. These last movements are effective to position the rollers 71 in operative relation to the running rails 79, and such rollers will maintain these positions and act to support the subtruck in its elevated relation to the track until the crossing or other obstruction has been passed and until such wheels are returned to their normal positions by the ramps on the distant side of the crossing or switch being passed. This return movement of the rollers 71 is effected by the convergence of the controlling ramps, and the lowering of the subtruck to its normal position is effected by the downward sloping of such ramps. If desired, some such means as spring pushed plungers and cooperating grooves may be employed for retaining the collars 74 in their operative and inoperative positions, and of course it is essential that the subtruck elevating and holding apparatus shall be so arranged as not to collide with any of the switch parts or transversely extending rails which make necessary the elevation of the track engaging rollers.

From the above description, it will be apparent that my invention provides a simple and rugged organization for the purpose set forth, and that all functions previously specified are effected in an advantageous manner. It will also be understood that in addition to such structural and functional features as are pointed out in the above description my invention presents other advantages; for example, the rails are so constructed that their flanges can be turned inwardly and their tread surfaces re-used at those locations where outside flanges are not desired, when such flanges through use in the ordinary manner have become detrimentally worn, and the rollers of the track engaging devices are so

designed as to also present double surfaces which can be used in succession by reversing their relation to the rail flanges and the sub-truck supporting pins. But it will be understood that if such reversible feature is not desired, the track engaging rollers may be formed with a single flange. Furthermore, it will be apparent that the longitudinally rigid character of the subtruck and its flange 10 engaging rollers will be effective to positively prevent any spreading of the main running rails with relation to the main truck wheels, and that this feature as well as an increased braking effectiveness will recommend the use of my invention in connection with trailer as distinguished from tractor trucks.

Other modes of applying the principle of my invention may be employed instead of the 20 one explained, change being made as regards the structure herein disclosed, provided the means stated by any of the following claims or the equivalent of such stated means be employed.

25 I therefore particularly point out and distinctly claim as my invention:—

1. In a system of the character described, a rail structure having spaced apart ways, and a device having wheels adapted for coacting with such ways, other wheels angularly positioned and movable with respect to said wheels, and motor means for controllably increasing the traction by said last-named wheels.

35 2. In a system of the character described, a rail structure having spaced apart way, and a device having wheels for coacting with such ways, other wheels angularly positioned and movable with respect to said wheels, and means for moving said other wheels or securing braking as desired.

3. In a system of the character described, a rail structure having spaced apart way, and a device having wheels adapted for coacting with such ways, other wheels angularly positioned and movable with respect to said wheels, a brake, and means for positioning said last-named wheels or operating the 50 brake.

4. In a system of the character described, a rail structure having a head and a flange, and a device having wheels adapted for coacting with such head and other wheels angularly positioned and movable with respect to said wheels and adapted for coacting with such flange, a brake, and a motor for positioning said last-named wheels or operating the 55 brake.

60 5. In a system of the class described, a rail structure having a head and a longitudinally interrupted flange, a ramp arranged adjacent to such rail structure at such interruption, and a device having a wheel adapted for coacting with such flange, said wheel be-

ing arranged for vertical movement by said ramp.

6. In a system of the character described, a track, and a truck for operating upon such track; said track having parallel rails with heads provided with flanges, and said truck including wheels adapted for coacting with such heads, other wheels angularly positioned and movable with respect to said wheels, optionally operable means for moving said last-named wheels, and track-mounted means for moving the same wheels for engagement or disengagement.

7. In a system of the character described, a track, and a truck for operating upon such track; said track having parallel rails with heads provided with flanges, and said truck including wheels adapted for coacting with such heads, brake shoes operable upon adjacent wheels, toggle means for operating said brake shoes, other wheels angularly positioned and movable with respect to said wheels, a motor for controlling the position of said last-named wheels and operating said toggle brake-means, and track-mounted means for moving the same wheels for disengagement or engagement.

8. In a system of the character described, a track, and a truck for operating upon such track; said track consisting of rails having flanged and unflanged heads and ramps operatively associated with such of said rails as have unflanged heads, and such truck consisting of a structure including wheels for coacting with said heads, rollers for coacting with such flanges, a support for such rollers, and means for vertically elevating said support and said rollers when such truck is operating upon the unflanged portions of such rail.

9. In a system of the character described, a track and truck; said track consisting of rails having projecting flanges, and said truck consisting of a frame including wheels for coacting with such rails, devices for coacting with such flanges, a support for such devices, and means for increasing the force with which such devices and said wheels bear against such flanges and rails, said means including cams for lifting said support and means for revolving said cams.

10. In a system of the character described, a track, and a truck for operating upon said track, said track consisting of flanged and unflanged rails, and a ramp operatively associated with such unflanged rails, and said truck consisting of a structure including wheels for coacting with such rails, devices for coacting with such flanges, and supports for said devices, said ramps being adapted for raising said support and said devices vertically.

11. In a system of the character described, a track and a truck, said track including flanged and unflanged rails, and ramps oper-

atively associated with such unflanged rails, and said truck including roller device for coacting with such flanges, a support for such devices, and rollers on said support, said rollers being arranged for coacting with such ramps.

12. In a system of the character described, a track and a truck; said truck consisting of rails having projecting flanges, and said truck including devices for coacting with such flanges, wheels for coacting with such rails, brakes for said wheels, a support for said devices, and means operable in one direction to lift said support and in another direction to both lift said support and apply such brakes.

13. In a system of the character described, a track and a truck; said track consisting of rails having projecting flanges, and said truck including devices for coacting with such flanges, wheels for coacting with such rails, brakes for said wheels, a support for said devices, and means operable in one direction to lift said support and in another direction to both lift said support and apply such brakes, said means consisting of a shaft carrying cams, and members connected to such support and brakes, said members being arranged for operation by such cams.

14. In a system of the character described, rails provided with flanges, and a truck provided with wheels for coacting with such flanges, said flanges being discontinuous in the vicinities of switches and crossings in order to permit of the elevation of such wheels.

15. In a system of the character described, rails having discontinuous flanges, a truck having means for normally engaging with such flanges, and means associated with such rails for positively and mechanically lifting such first named means where such discontinuities of said flanges occur.

16. In a system of the character described, rails having discontinuous portions, a truck having devices for normally coacting with such portions, means associated with such rails for mechanically moving such devices away from such rails where such discontinuities of such portions occur, and means for holding such devices in such removed positions until such discontinuities terminate.

Signed by me this 14th day of February, 1929.

55 ALCUIN E. KINTNER.
